HEEL SUPPORT FOR DISPLAYING WOMEN'S SHOES

William V. Baron, 10910 Clayton Road,
Frontenac, Mo.

Filed Apr. 18, 1960, Ser. No. 60,222

Term of patent 3½ years

(Cl. D80—9)

FIG. 1

I claim:

The ornamental design for a heel support for displaying women's shoes, substantially as shown and described.
